(57) **ABSTRACT**

According to a first example of the disclosure, a tile light luminaire (120) is proposed, which suitable for laying in the T-bar grid (11) of a suspended ceiling assembly (10), the tile light luminaire (120) having a luminaire housing (220) with an outer housing periphery (120z) being smaller than the inner periphery (10z) of a T-bar grid cell, and wherein a first periphery section (120z1) of the housing periphery (120z) of the tile light luminaire is structured for abutment with a section part of the periphery of the T-bar grid cell, and a second periphery section (120z2) of the housing periphery (120z) of the tile light luminaire is structured for abutment with a section part (130z2) of the periphery of a ceiling tile (130). As the tile light luminaire (120) has an outer periphery dimension (120z), which is smaller than the inner periphery dimension (10z) of a T-bar grid cell of a suspended ceiling assembly (10), such tile light luminaire is suitable to be interchanged between T-bar grids having different dimensions, either square or rectangular.

**TILE LIGHT LUMINAIRE FOR A
SUSPENDED TILE LIGHT CEILING
ASSEMBLY, AS WELL AS SUCH SUSPENDED
TILE LIGHT CEILING ASSEMBLY**

**CROSS-REFERENCE TO PRIOR
APPLICATIONS**

This application is the U.S. National Phase application under 35 U.S.C. § 371 of International Application No. PCT/EP2022/085180, filed on Dec. 9, 2022, which claims the benefit of European Patent Application No. 21213942.2, filed on Dec. 13, 2021. These applications are hereby incorporated by reference herein.

TECHNICAL FIELD

The present disclosure relates to a tile light luminaire suitable for laying in the T-bar grid of a suspended tile light ceiling assembly. The disclosure also pertains to a suspended tile light ceiling assembly implementing a T-bar grid and such tile light luminaire.

BACKGROUND OF THE INVENTION

Indoor lighting applications in office spaces, supermarkets or other large area spaces are often based on in a suspended tile light ceiling assembly implementing a T-bar grid and tile light luminaires, which are laid or mounted in a grid cell of the T-bar grid. Such suspended tile light ceiling assemblies are mounted at some distance from the ceiling in a suspended manner, and accordingly hides the building infrastructure, such as cables, air-conditioning piping, heating and water piping, etc. In addition to the tile light luminaires, which provide the lighting functionality, the remainder of the suspended T-grid is occupied by ceiling tiles, often manufactured from compacted mineral fibers. Such material can be non-flammable. Additionally, such fiber ceiling tiles provide, next to an improved visual appearance and flame resistance, also sound proofing by the damping of sound and thus improve the acoustics in the office space or room.

Such suspended tile ceiling assemblies implementing a T-bar grid are available in standardized dimensions, which dimensions however might differ in different countries. A common size of a grid cell surface area is 600 mm×600 mm, however other grid cell dimensions are used, such as 625 mm×625 mm and 675 mm×675 mm. Next to the so-called square T-grid dimensions, also suspended ceiling assemblies implementing a rectangular T-bar grid dimension are commercially available.

For each type of suspended tile light ceiling assembly implementing a square or rectangular T-bar grid of a certain dimension, tile light luminaires and mineral fibre ceiling tiles are used, having more or less corresponding dimensions, thus filling the whole surface area of a T-bar grid cell. This situation limits a more versatile and flexible use of the T-bar grid as to its illumination ceiling area and also limits use of other types and sizes of tile light luminaires.

Accordingly, it is a goal of the present disclosure to provide an improved light, which is interchangeable between suspended ceiling assemblies implementing T-bar grids of a different dimension and allow an adaptive lighting visual with a large variety of lighting patterns across the suspended ceiling surface.

US2019/0203465A1 discloses a ceiling tile with integrated lighting and ceiling system.

2

SUMMARY OF THE INVENTION

According to a first example of the disclosure, a combination of at least a tile light luminaire and a ceiling tile is proposed, said combination being configured for laying/being mounted into a T-bar grid cell of a T-bar grid of a suspended ceiling assembly available in standard dimensions,

wherein the tile light luminaire has a luminaire housing with an outer housing periphery being smaller than the inner periphery of the T-bar grid cell, wherein a first periphery section of the housing periphery of the tile light luminaire is structured for abutment with a section part of the periphery of the T-bar grid cell, and a second periphery section of the housing periphery of the tile light luminaire is structured for abutment with a section part of the periphery of a ceiling tile,

wherein the periphery of the ceiling tile having a section part being complementary to a section part of the periphery of a tile light luminaire,

wherein the tile light luminaire has a tile light surface and the ceiling tile has a ceiling tile surface, in mounted configuration of said combination a cell surface area of the T-bar grid cell is essentially completely covered by said combination,

wherein the second periphery section is provided with a support rail structured to support the section part of the periphery of a ceiling tile, and

wherein the support rail is provided with mounting pins for interaction with the section part of the periphery of a ceiling tile.

As the tile light luminaire has an outer periphery dimension, which is smaller than the inner periphery dimension of a T-bar grid cell of a suspended ceiling assembly, such tile light luminaire is suitable to be interchanged between T-bar grids having different dimensions, either square or rectangular. As the housing periphery of the tile light luminaire is capable of interacting through abutment with both the inner periphery of the T-bar grid by means of a first periphery section of the housing periphery of the tile light luminaire and the outer periphery of a ceiling tile by means of a second periphery section of the housing periphery of the tile light luminaire, various lighting patterns can be established across the suspended ceiling surface. Typically, the surface area of the grid cell is essentially completely, i.e. for at least 90%, such as 95% up to and including 100%, covered by at least one tile light luminaire and at least one (complementary) ceiling tile.

For an effective abutment with the inner periphery of the T-bar grid cell, the first periphery section comprises at least one straight periphery part and more preferably comprises at least two straight periphery parts. In addition, in an example of a tile light luminaire having a specific geometry, the first periphery section comprises at least one supporting point.

Furthermore, in an specific example of the disclosure, also the second periphery section comprises at least one straight periphery part. The second periphery section may also comprises at least one curved periphery part, which curved periphery section can be a circle arc or elliptical periphery section. This allows for the creation of lighting ceiling surfaces having a variety of curved patterns.

In a particular example, the at least one circle arc periphery section is a 90° or 180° circle arc.

In particular, for both the first and second periphery sections, the at least two straight periphery parts of that periphery section may have an inclined orientation with respect to each other. Preferably, the inclination is 90° or

smaller, in particular 30°, 45°, 60° or 90°. Tile light luminaires having such specific outer periphery designs of their luminaire housing, can be used complex and appealing lighting pattern designs, which deviate significantly from the known straight-forward square or rectangular designs.

In an advantageous example, the second periphery section is provided with a support rail structured to support the section part of the periphery of a ceiling tile, preferably such that tile light surface and the ceiling tile surface are mutually flush. In particular, the support rail is provided with mounting pins for interaction with the section part of the periphery of a ceiling tile, and/or the support rail is provided with venting openings. In addition, the support rail may be provided with one or more mounting openings, e.g. for mounting or accommodating one or more sensor elements.

In a further example of the disclosure, the tile light luminaire further comprising at least one light emitting source within the luminaire housing and structured to emit light and wherein the luminaire housing is provided with a light exit window for the light being emitted, wherein the light exit window is provided with window parts, which are opaque to the light being emitted. Herewith an additional design feature is created, which allows for designing other lighting patterns across the suspended ceiling surface with a sophisticated surface illumination.

The disclosure also pertains to a suspended tile light ceiling assembly implementing a T-bar grid and a plurality of tile light luminaires suitable for laying in the T-bar grid as outlined in this specification.

In particular, the suspended tile light ceiling assembly comprises at least one ceiling tile suitable for laying in the T-bar grid, the periphery of the ceiling tile having a section part being complementary to a section part of the periphery of a tile light luminaire. Accordingly, such set of a tile light luminaire and ceiling tile having complementary periphery sections effectively occupy jointly the whole surface area of a T-bar grid cell and subsequently can be used to design complex and appealing lighting pattern.

In a further beneficial example, the plurality of tile light luminaires is composed of a first group of tile light luminaires configured to emit light having a first dominant peak wavelength and at least one further group of tile light luminaires configured to emit light having a further dominant peak wavelength, the further dominant peak wavelength being different from the first dominant peak wavelength.

With this example, the light emitted by the tile light luminaires of the different groups can have different properties. In particular, the emitted light spectrum can differ per tile light luminaire using in the suspended tile light ceiling assembly. A first tile light luminaire or a first group of tile light luminaire can emit a spectrum that provides functional light, such as visible light optimized for office work, whereas a further tile light luminaire or a further group of tile light luminaires emits light having a biological effect (such as a melanopic effect or for disinfection using UV light). In another example, one group of luminaires may emit functional white light, whereas another group can emit a lower intensity colored light pattern for a decorative purpose.

Accordingly, in one example outlined above both first and further dominant peak wavelengths are within the visible light wavelength range, whereas in the other example outlined above the first dominant peak wavelength is within the visible light wavelength range and the further dominant peak wavelength is within the invisible light (e.g. UV light) wavelength range.

In a further advantageous example of the disclosure, the first and further group of tile light luminaires emit light in different angular directions relative to the orientation of the ceiling. For example, the first tile light luminaire or the first group of tile light luminaire can emit a spectrum that provides functional light, such as visible light optimized for office work, can directed predominantly downwards, whereas the further tile light luminaire or the further group of tile light luminaires emits light providing a biological or aesthetical effect directed predominantly at angles deviating substantially from a normal to the ceiling.

BRIEF DESCRIPTION OF THE DRAWINGS

15 The invention will now be discussed with reference to the drawings, which show in:

FIGS. 1a and 1b a first and second example of a suspended ceiling assembly implementing a T-bar grid and tile light luminaires according to the state of the art;

20 FIG. 2 an example outlining the principle of the disclosure;

FIGS. 3a-3h non-limiting examples of embodiments of a suspended ceiling assembly implementing a T-bar grid and tile light luminaires according to the disclosure;

25 FIGS. 4a and 4b an example of a tile light luminaires according to the 15 disclosure;

FIGS. 5a and 5b detailed views of a suspended ceiling assembly implementing a T-bar grid and tile light luminaires according to the disclosure;

30 FIGS. 6a-6f further non-limiting examples of embodiments of a suspended ceiling assembly implementing a T-bar grid and tile light luminaires according to the disclosure;

FIG. 7 a further example of a suspended ceiling assembly according to the disclosure;

35 FIGS. 8a-8c further non-limiting examples of a tile light luminaires according to the disclosure.

DETAILED DESCRIPTION OF THE INVENTION

40 For a proper understanding of the invention, in the detailed description below corresponding elements or parts of the invention will be denoted with identical reference numerals in the drawings.

45 FIGS. 1a and 1b depict a first and second example respectively of a suspended ceiling assembly implementing a T-bar grid and tile light luminaires according to the state of the art.

50 Suspended ceiling assemblies (denoted with reference numeral 10) are often used for indoor lighting applications in office spaces, supermarkets or other large area spaces. Such suspended ceiling assemblies is mounted at some distance from the ceiling in a suspended manner, and accordingly hides the building infrastructure, such as cables, air-conditioning piping, heating and water piping, etc. In addition to the tile light luminaires 12, which provide the lighting functionality, the remainder of the suspended T-grid can be occupied by mineral fibre ceiling tiles (not shown in FIGS. 1a and 1b), which next to an improved visual appearance, 55 also provide the damping of sound and thus improve the acoustics in the office space or room. Such material is often also non-flammable, thus providing some flame resistance.

60 Suspended ceiling assemblies implement a cartesian T-bar grid denoted with reference numeral 11, which grid is composed of grid bars 11x and 11y forming a cluster of (T-bar) grid cells 23. The grid bars 11x and 11y have a T-shape, and a tile light luminaire 12 can be mounted or laid

in the grid cell, whereby the whole outer periphery **12z** of tile light luminaire **12** is supported by the inner periphery **10z** of each grid cell/T-bars **11x** and **11y**.

Such suspended ceiling assemblies **10** implementing a T-bar grid **11** are available in standardized dimensions, which dimensions however might differ in different countries. A common size of a grid cell surface area is 600 mm×600 mm, however other grid cell dimensions are used, such as 625 mm×625 mm and 675 mm×675 mm. Next to the so-called square T-grid dimensions, also suspended ceiling assemblies **10** implementing a rectangular T-bar grid dimension are commercially available.

For each type of suspended ceiling assembly implementing a square or rectangular T-bar grid of a certain dimension, tile light luminaires **12** and mineral fibre ceiling tiles **13** are used, having more or less corresponding outer dimensions or peripheries **12z** and **13z** respectively, thus filling the whole surface area of a T-bar grid cell. Examples of tile light luminaires **12** and mineral fibre ceiling tiles **13** occupying the whole area of a T-bar grid cell are shown in FIG. 1a.

There are configurations, as shown in FIG. 1b, wherein the tile light luminaire **12'** has a luminaire housing with an outer periphery dimension, which is significantly smaller than the inner periphery dimension **10z** of the T-bar grid cell. Accordingly, additional wide frame rim members or end pieces **14** are used, which are placed around the tile luminaire **12'** in order to fill the gap and to properly cover the whole surface area of the T-bar grid cell.

However, both applications as shown in FIGS. 1a and 1b limit a more versatile and flexible use of the T-bar grid **11** as to its illumination ceiling area and also limits use of other types and sizes of tile light luminaires.

FIG. 2 depicts the principle of the disclosure. It shows schematically and not to scale an example of a suspended ceiling assembly **10** implementing a T-bar grid **11** composed of intersecting T-bars **11x-11y** and a tile light luminaire **120** according to the disclosure. In particular, a tile light luminaire (denoted with reference numeral **120**) is proposed, which luminaire **120** is suitable for laying in the T-bar grid **11** of a suspended ceiling assembly **10**. As depicted in more detail in FIGS. 4a and 4b, the tile light luminaire **120** according to the disclosure has a luminaire housing **220**. The outer periphery **120z** of the tile light luminaire **120**/luminaire housing **220** is smaller than the inner periphery **10z** of a T-bar grid cell formed by intersecting T-bars **11x** and **11y**, as depicted in FIG. 2.

It should be understood that in this disclosure the outer periphery **120z** of the tile light luminaire **120** and the inner periphery **10z** of a T-bar grid cell are considered as the circumference of both elements extending within the plane formed by the T-bar grid **11** of the suspended ceiling assembly **10**.

In particular, and as shown in FIG. 2 (and in the several non-limiting examples depicted in FIGS. 3a-3h and 6a-6b), the outer periphery (or circumference) **120z** of the luminaire housing **220** of the tile light luminaire **120** can be identified by a first periphery section (in all Figures denoted with **120z1**) and a second periphery section (in all Figures denoted with **120z2**). Combined, the length dimensions of both first periphery section **120z1** and second periphery section **120z2** make up for the overall length dimension of the outer periphery **120z** of the luminaire housing **220** of the tile light luminaire **120**.

According to the disclosure, the first periphery section **120z1** is structured for mounting abutment with the periphery **10z** of the T-bar grid module or cell. Furthermore, the second periphery section **120z2** of the housing periphery

120z of the tile light luminaire **120** is structured for mounting abutment with a section part **130z2** of the periphery **130z** of a ceiling tile **130**.

As shown in FIG. 2, the tile luminaire **120** and the ceiling tile **130** have complementary periphery configurations. Accordingly, when combined together as mentioned before, both the tile luminaire **120** and the ceiling tile **130** occupy the whole surface area of the T-bar grid cell.

As the tile light luminaire **120** has an outer periphery dimension **120z**, which is smaller than the inner periphery dimension **10z** of a T-bar grid cell of a suspended ceiling assembly **10**, such tile light luminaire **120** can be exchanged between T-bar grids having different dimensions, either square or rectangular. As the housing periphery **120z** of the tile light luminaire **120** is capable of interacting through abutment with both the inner periphery **10z** of the T-bar grid by means of its first periphery section **120z1** as well as with the outer periphery **130z** of a ceiling tile **130** by means of its second periphery section **120z2** of the housing periphery **120z**, various lighting patterns can be established across the suspended ceiling surface. Likewise, the ceiling tile **130** has a complementary first periphery sections **130z1** for abutment with the inner periphery **10z** of the T-bar grid cell.

Various non-limiting examples of such various lighting patterns are depicted in the examples shown in FIGS. 3a-3h.

For an effective abutment with the inner periphery **10z** of the T-bar grid module/cell **23**, the first periphery section **120z1** has at least one straight periphery part and more preferably comprises at least two straight periphery parts. See FIGS. 3a, 3b, as well as FIGS. 3e and 3f. As shown in the FIGS. 3a-3h the surface area of the grid cells **23** are essentially completely covered by at least one tile light luminaire **120,220** and at least one (complementary) ceiling tile **130**.

In the examples of FIGS. 3a-3b-3c and 3d two straight periphery parts of the first periphery section **120z1** of the tile light luminaire **120** have an inclined orientation with respect to each other, in the Figures mentioned is the inclination is 90°. Accordingly, the tile light luminaire **120** can be effectively positioned in one of the corners of the T-bar grid cell with a minimum of space between the luminaire housing and the T-bar grid. Herewith an optimal light emitting ceiling surface can be created using multiple tile light luminaires **120** in adjoining T-bar grid cells, as shown in FIGS. 3a-3d.

In the examples of FIGS. 3a and 3c, the remaining area of the T-bar grid cells is occupied and covered by a ceiling tile **130** having a periphery section **130z2** which is complementary to the second periphery section **120z2** of the tile light luminaire **120**. Accordingly, the second periphery section **120z2** of the tile light luminaire **120** is structured to abut with the complementary periphery section **130z2** of the ceiling tile **130**, thus effectively covering the T-bar grid cell. Likewise, the ceiling tile **130** has a complementary first periphery sections **130z1** for abutment with the inner periphery **10z** of the T-bar grid cell.

In the examples of FIGS. 3b and 3d, two tile light luminaires **120** are mounted at different locations (corners) in the same T-bar grid cell and accordingly the complementary ceiling tile **130** of these two examples has a second periphery section **130z2** structured to abut with the second periphery sections **120z2** of both tile light luminaires **120**.

When several tile light luminaires **120** are intended to be mounted within the same T-bar grid cell, these tile light luminaires **120** can be identical or congruent to each other or can have different periphery configurations. When mounting multiple tile light luminaires **120** in the same T-bar grid cell, the remaining open surface area of the T-bar grid cell is to

be occupied/covered by one or more corresponding ceiling tiles **130** having complementary first and second periphery sections **130z1-130z2** for abutment with either the inner periphery **10z** of the T-bar grid cell and the tile light luminaires **120**.

The inclined orientation between the straight periphery parts of the first periphery section **120z1** of the tile light luminaire **120** with respect to each other can be 90° or smaller, in particular 30°, 45°, 60° or 90°, all depending on the geometry of the T-bar grid cells of the suspended tile light ceiling assembly. Tile light luminaires **120** having such specific outer periphery designs of their luminaire housing **220**, can be used complex and appealing lighting pattern design, which deviate significantly from the known straightforward square or rectangular designs.

In addition, in the examples of FIGS. **3e** and **3h**, the tile light luminaire **120** has a specific geometry, wherein the first periphery section **120z1** comprises at least one supporting point **120z1'**. In FIG. **3e**, said supporting point **120z1'** is formed as the apex (vertex) of the equilateral rectangle shaped tile luminaire **120**, of which both the apex (vertex) as its base edge form the first periphery section **120z1** for abutment with the inner periphery **10z** of the T-bar grid cell. The second periphery section **120z2** of the triangle shaped tile luminaire **120** is composed of two separate straight periphery parts forming the two other vertices of the triangle.

In general, it is noted that the tile luminaire **120** can have an outer periphery **120z** formed as a regular polygon, with equiangular angles and equilateral sides. An example of such polygon configuration is depicted in FIG. **3f**. In this example, Four complementary triangle shaped ceiling tiles **130** are used for abutment with their second periphery section **130z2** with the second periphery sections **120z2** of the polygon shaped tile luminaire **120** and with their first periphery sections **130z1** with (the corners of) the inner periphery **10z** of the T-bar grid cell.

In FIG. **3e**, the tile luminaire **120** has an outer periphery **120z** formed as an equilateral rectangle. Furthermore, two complementary triangle shaped ceiling tiles **130** are used for abutment with their second periphery section **130z2** with the second periphery sections **120z2** of the equilateral rectangle shaped tile luminaire **120** and with their first periphery sections **130z1** with (the corners of) the inner periphery **10z** of the T-bar grid cell.

In the example of FIG. **3h** the tile luminaire **120** has a square configuration and abuts with its four corners, functioning as contact points or vertexes **120z1'** forming the first periphery section **120z1**, against the inner periphery **10z** of the T-bar grid cell. Four complementary triangle shaped ceiling tiles **130** are used for abutment with their second periphery section **130z2** with the second periphery sections **120z2** of the square tile luminaire **120** and with their first periphery sections **130z1** with (the corners of) the inner periphery **10z** of the T-bar grid cell.

A rectangular configuration of the tile luminaire **120** is also a possible example, for mounting in a rectangular T-bar grid configuration.

A variant on the example of FIG. **3h** is depicted in FIG. **3g**, wherein the tile luminaire **120** has an outer periphery configuration shaped as a circle. The circle periphery **120z** abuts with its four contact or tangent points **120z1** with the inner periphery **10z** of the T-bar grid cell. Four complementary quarter circle shaped ceiling tiles **130** are used for abutment with their second periphery section **130z2** with the arc shaped second periphery sections **120z2** of the circle shaped tile luminaire **120** and with their first periphery

sections **130z1** with (the corners of) the inner periphery **10z** of the T-bar grid cell. Likewise the outer periphery configuration of the tile light luminaire **120** can be shaped as an ellipse.

5 Likewise, also the second periphery section **120z2** of the outer periphery **102z** of the tile light luminaire **120** may comprise one or more (two) straight periphery parts, as depicted in FIGS. **3a-3b-3e** and **3f**. These straight periphery parts of the second periphery section **120z2** interact through 10 abutment with corresponding complementary straight periphery parts of the second periphery section **130z2** of one or more corresponding ceiling tiles **130**.

The second periphery section **120z2** may also comprises 15 at least one curved periphery part, which curved periphery section can be a circle arc or elliptical periphery section. In particular examples, the at least one circle arc periphery section is a 90° or 180° circle arc. Examples of quarter circle (90°) examples are shown in FIGS. **3c** and **3d**. This allows 20 for the creation of lighting ceiling surfaces having a variety of curved patterns.

FIGS. **4a** and **4b** disclose in more detail an example of a tile light luminaire **120** according to the disclosure, whereas FIGS. **5a** and **5b** disclose such tile light luminaire **120** mounted or laid in a suspended tile light ceiling assembly 25 **10-11** according to the disclosure. The tile light luminaire **120** according to the disclosure may have an irregular shape as shown in FIGS. **2** and **3a-3h**. The tile light luminaire **120** comprises at least one light emitting source (not shown in the Figures) within the luminaire housing **220**. The tile light luminaire **120** and in particular the luminaire housing **220** 30 has an outer periphery **120z** for interaction with both the inner periphery **10z** of a T-bar grid cell and the outer periphery of a complementary ceiling tile **130**.

For achieving a proper abutment with the complementary 35 ceiling tile **130**, the second periphery section **120z2** of the outer periphery **120z** of the tile luminaire **120** is provided with a support rail **140**. The support rail **140** is mounted to the tile luminaire **120** and preferable made from a rigid 40 material, such as metal. The support rail **140** is structured to support the section part **130z2** of the periphery **130z** of a ceiling tile **130**, such that tile light surface and the ceiling tile surface are mutually flush.

In particular, the support rail **140** is provided with mounting 45 pins **141** for interaction with the section part **130z2** of the periphery of a ceiling tile **130**. The mounting pins **141** protrude from the support rail **140** and may function as rest stops for the section part **130z2** of the periphery **130z** of a ceiling tile **130**. This ensures a proper and reliable support 50 for the ceiling tile **130** within the T-bar grid cell.

The mounting pins **141** furthermore create a small gap 55 between the luminaire house **220** and the adjoining ceiling tile. Herewith it is possible to dissipate heat generated by the light emitting source of the tile luminaire **120** easily. In addition, the support rail **140** can be provided with venting openings **142**, which allow ventilation of air across the suspended ceiling assembly **10** through the venting openings **142** and the gap between the luminaire house **220** and the adjoining ceiling tile.

In addition, the support rail **140** may be provided with one 60 or more mounting openings, e.g. for mounting or accommodating one or more sensor elements (not shown), for example for detecting motion below the suspended ceiling assembly **10** in the room, to a humidity level of the air, or a light intensity level. Next to presence or movement detectors (usually PIR sensors), which switch off the light when no person is in the room, and daylight sensors, to dim the light in case there is sufficient daylight in the room, other 65

sensors may be related to sound or camera-based (to detect presence, density of occupants, or even the type of activity in the room), or to the air quality in the room (humidity, or pollutants like carbon monoxide, carbon dioxide, nitrogen dioxide, ozone).

The mounting opening or a slot in the support rail 140 can also accommodate communication modules based on, for instance, RF communication, LiFi communication, or acoustic (ultrasound) communication, to enable wireless communication between the luminaires or between the luminaires and other communication modules in the room.

The sensor elements might generate electronic signals based on which the control circuitry of the suspended ceiling assembly 10 is controlled, e.g. for switching on or off the tile light luminaires. In another example, the sensor elements accommodated in the rail 140 may detect heat or smoke and subsequently activate a sprinkler system.

More complex lighting patterns of lighting ceiling surfaces having a variety of curved patterns can be established, as shown in the examples of FIGS. 6a-6f.

The suspended tile light ceiling assembly 10-11 of both FIG. 6a and FIG. 6b implements, next to standard known ceiling tiles 13, which cover a T-bar grid cell surface area completely, also quarter circle tile light luminaires 120 as outlined in FIG. 3c together with a complementary shaped ceiling tile 130.

The suspended tile light ceiling assembly 10-11 of FIG. 6c implements, next to standard known tile luminaires 12 and standard known ceiling tiles 13, which both cover a T-bar grid cell surface area completely, also quarter circle tile light luminaires 120 as outlined in FIG. 3c together with a complementary shaped ceiling tile 130.

The suspended tile light ceiling assembly 10-11 of FIG. 6d implements, next to standard known ceiling tiles 13, which cover a T-bar grid cell completely, also different groups of tile light luminaires 120. A first group consists of a plurality of rectangular shaped tile light luminaires 120-d1 as outlined in FIG. 3a-3b. The suspended tile light ceiling assembly 10-11 also comprises two further groups of differently curved tile light luminaires 120-d2 and 120-d3. Likewise, complementary shaped ceiling tiles 130 for each group of tile light luminaires 120-d1; 120-d2; 120-d3 are used to cover the corresponding T-bar grid cells.

The suspended tile light ceiling assembly 10-11 of FIG. 6e implements, next to standard known ceiling tiles 13, which cover a T-bar grid cell completely, also two groups of quarter circle tile light luminaires 120-e1 and 120-e2 as outlined in FIG. 3d together with a complementary shaped ceiling tile 130 as shown in FIG. 3d. In this example, the two groups of tile light luminaires 120-e1 and 120-e2 have the same quarter circle outer periphery dimension 120z.

The suspended tile light ceiling assembly 10-11 of FIG. 6f implements, next to standard known ceiling tiles 13, which cover a T-bar grid cell completely, also two groups of quarter circle tile light luminaires 120-f1 and 120-f2 having the different curved outer periphery dimensions 120z. Also in this example, complementary shaped ceiling tiles 130 for each group of tile light luminaires 120-f1 and 120-f2 are used to cover the corresponding T-bar grid cells.

The examples of FIGS. 6e and 6f implement different groups of tile light luminaires 120-e1; 120-e2; 120-e3; 120-f1; 120-f2 having different outer periphery configurations, allowing the creation of a variety of curved patterns. In addition, the different groups of tile light luminaires may be structured to emit light having a dominant peak wavelength, which dominant peak wavelength differ from the dominant peak wavelength of each other group.

With this example, the light emitted by the tile light luminaires of the different groups can have different properties. In particular, the emitted light spectrum can differ per tile light luminaire group mounted in the suspended tile light ceiling assembly 10-11.

For example, referring to FIGS. 6e and 6f, the first tile light luminaire 120-e1 (120-f1) or the first group of tile light luminaires 120-e1 (120-f1) can emit a spectrum that provides functional light, such as visible light optimized for office work, whereas the other tile light luminaire 120-e2 (120-f2) or the further group of tile light luminaires 120-e2 (120-f2) emits light having a biological effect (such as a melanopic effect or for disinfection using UV light).

In another example, one first group of tile light luminaires 120-e1 (120-f1) may emit functional white light, whereas another further group of tile light luminaires 120-e2 (120-f2) could emit a lower intensity colored light pattern for a decorative purpose. Additional functional or aesthetic effects can be achieved with the use of a further, third or even fourth, group of tile light luminaires emitting light with a different dominant peak wavelength, either in the visible or invisible wavelength range.

In a further advantageous example of the disclosure as depicted in FIG. 7, the first 120-e1 (120-f1) and further 120-e2 (120-f2) group of tile light luminaires emit light in different angular directions relative to the orientation of the T-bar ceiling grid 11. For example, the first tile light luminaire 120-e1 (120-f1) or the first group of tile light luminaires 120-e1 (120-f1) can emit a spectrum that provides functional light, such as visible light optimized for office work, can directed predominantly downwards at an angle of 90° relative to the T-bar ceiling grid 11. The further tile light luminaire 120-e2 (120-f2) or the further group of tile light luminaires 120-e2 (120-f2) can emit visible light with a different dominant peak wavelength or light providing a biological or aesthetical effect predominantly at angles (e.g. 45° and 135° deviating substantially from a normal to the grid ceiling 11).

Each tile luminaire 120 may have its own power supply and driving circuitry. Alternatively, power (and data) supply between the tile luminaire can be shared, e.g. each group of light luminaires 120-e1 (120-f1) and 120-e2 (120-f2) can have one group dedicated power supply and driving circuitry. In another example, tile luminaires with a small light emitting window 222 may receive power from a neighboring tile luminaire with a larger light emitting window 222.

In all examples shown in the Figures, the tile light luminaire 120 comprising at least one light emitting source (not shown in the Figures) within the luminaire housing 220. The at least one light emitting source is structured to emit light having a dominant peak wavelength. In addition, the luminaire housing 220 is provided with a light exit window 221 for the light being emitted. An example of such tile light luminaire 120 is depicted in more detail in FIG. 8a. The light emitting source can be a LED light device.

In further example shown in FIGS. 8b and 8c, the light exit window 221 is provided with window parts 221a, which allow translucent to the light being emitted and windows parts 221b which are opaque to the light being emitted. Herewith an additional design feature is created, which allows for designing other lighting patterns across the suspended ceiling surface with a sophisticated surface illumination. The opaque/non-light-emitting window parts 221b may be made of an opaque plastic component material or from same sound-proofing material, such as compacted mineral fibers, as used for regular non-light-emitting tiles 13 of FIG. 1a.

11

Alternatively, as shown in FIG. 8c, the light exit window 221 can be subdivided into window part areas 221c that differ in shape (e.g., Voronoi polyhedra) and wherein each windows part area 22c may provide a beam of downwards directed light.

In all examples shown in the Figures, the shape at the outer edge of each tile light luminaire 120 as well as the complementary shaped non-light-emitting ceiling tile 130 and regular non-light-emitting tile 13 is such, that the surface transition between every pair of neighboring tiles is flush. This means that between neighboring tiles no discontinuities in the surface occurs, and that in the event of neighboring tile light luminaires the neighboring light exit windows are flush, such that the properties of the emitted light across the surface transition are identical.

The invention claimed is:

1. A combination of at least a tile light luminaire and a ceiling tile, said combination being configured for laying/ being mounted into a T-bar grid cell of a T-bar grid of a suspended ceiling assembly available in standard dimensions, said combination comprising:

the tile light luminaire comprising a luminaire housing with an outer housing periphery, the whole outer housing periphery being smaller than and supported by the inner periphery of the T-bar grid cell, wherein a first periphery section of the housing periphery of the tile light luminaire is structured for abutment with a section part of the periphery of the T-bar grid cell, and a second periphery section of the housing periphery of the tile light luminaire is structured for abutment with a section part of the periphery of a ceiling tile, wherein the periphery of the ceiling tile having a section part being complementary to a section part of the periphery of a tile light luminaire, wherein the tile light luminaire has a tile light surface and the ceiling tile has a ceiling tile surface, in mounted configuration of said combination a cell surface area of the T-bar grid cell is essentially completely covered by said combination, wherein the second periphery section is provided with a support rail structured to support the section part of the periphery of a ceiling tile, wherein the support rail is provided with at least one vent opening, wherein the support rail is provided with mounting pins for interaction with the section part of the periphery of a ceiling tile, and wherein the mounting pins are fixedly attached to the support rail in a manner that creates a gap between the

12

luminaire housing and said section part of the periphery of the ceiling tile, thereby permitting dissipation of heat generated within the luminaire housing thorough said gap and said vent opening.

5 2. The combination according to claim 1, wherein the first periphery section comprises at least one straight periphery part.

3. The combination according to claim 1, wherein the first periphery section comprises at least two straight periphery parts.

10 4. The combination according to claim 1, wherein the first periphery section comprises at least one supporting point.

5. The combination according to claim 1, wherein the second periphery section comprises at least one straight periphery part.

15 6. The combination according to claim 1, wherein the second periphery section comprises at least one curved periphery part.

7. The combination according to claim 3, wherein the at least two straight periphery parts of the periphery section are inclined with respect to each other.

20 8. The combination according to claim 1, wherein support rail supports the section part of the periphery of a ceiling tile such that tile light surface and the ceiling tile surface are mutually flush.

9. The combination according to claim 1, wherein the support rail is provided with venting openings.

25 10. The combination according to claim 1, wherein the support rail is provided with one or more mounting openings for mounting one or more sensor elements.

30 11. The combination according to claim 1, further comprising at least one light emitting source within the luminaire housing and configured to emit device light having a dominant peak wavelength within a visible light wavelength range and wherein the luminaire housing is provided with a light exit window for the light being emitted.

40 12. A suspended tile light ceiling assembly implementing a T-bar grid and a plurality of combinations of tile light luminaire and ceiling tile suitable for laying in the T-bar grid according to claim 1.

45 13. The suspended tile light ceiling assembly according to claim 12, wherein the plurality of tile light luminaires is composed of a first group of tile light luminaires configured to emit device light having a first dominant peak wavelength and at least one further group of tile light luminaires configured to emit device light having a further dominant peak wavelength, the further dominant peak wavelength being different from the first dominant peak wavelength.
